BRACKET FOR MOUNTING ANTENNA MASTS

John Wilson Shur, Sea Cliff, N. Y., assignor to
Shur-Antenna-Mount Inc., Sea Cliff, N. Y., a
corporation of New York

Application April 21, 1945, Serial No. 589,608

15 Claims. (Cl. 248—43)

1

My invention relates to improvements in devices for mounting antenna masts, and more particularly to an improved device which may be used for mounting radio antennas, for receiving or sending apparatus, on roofs.

This application is a continuation-in-part of my pending application Serial No. 568,319, filed December 15, 1944, for "Antenna mounting," and the present invention is an improvement on the antenna mounting device described and claimed in said application.

The antenna mounting disclosed in said application comprises a metal platform adapted to be mounted in a horizontal position on a suitable support preferably on the ridge of a roof. The mounting includes a vertical member for holding an antenna mast, such as a pipe or tubular member, attached to the upper surface of the platform, and braces attached to opposite edges of the platform by a pivoted connection and adapted to be attached to the sloping sides of the roof, regardless of the angle, to hold the platform in horizontal position. In a particular form of the mounting, the braces are relatively long links hinged to two diagonally opposite corners of the platform and each brace is provided with a hinged leaf or plate for securing the end of the brace to any surface, such as the sloping surface of a roof.

One of the problems involved in the construction of antenna mounting devices of the type disclosed in the above-mentioned application, is the means for providing the hinged or pivoted joints between the platform and the tie-rod or link, and between the projecting end of the link and the anchor plate for anchoring the projecting end of the link to the roof or other supporting structure. The present invention provides a novel mounting device in which interchangeable means is provided for forming both of the hinged joints of the device.

According to a preferred form of construction, this means includes a sheet metal anchor member having a pivot connection adapted to be pivoted to either end of the link and a bearing section adapted to be attached to a corner of the platform or to the surface of the supporting structure, such as the sloping surface of a roof. The provision of a pivoting connection member of this type not only facilitates the manufacture of the device, but also provides an antenna mast mounting device which has versatile features of construction permitting of ready assembly and installation.

In one form of the invention the improved

2

antenna mounting device therefore comprises a substantially flat relatively heavy metal platform member, preferably rectangular or square shaped, an upright means attached to and extending from the upper surface of the platform member for holding an antenna mast, a link pivotally connected to each of two opposite edges or diagonally opposite corners of the platform member, the links being adapted to extend out to the sloping sides of a roof or other structural member, and an anchor means pivotally connected to at least one end of each of said links and adapted to be attached to the roof or structural member or the platform member, the anchor means comprising a flat sheet metal web having a pair of integral webs extending therefrom and providing a pair of ears to which an end of a link is attached by a pivot connection.

In a more specific sense the improved anchor member comprises a flat right triangular-shaped sheet metal web, a reinforcing web integral with said triangular-shaped web and extending normal thereto from each of the equal edges of said triangular-shaped web, the ears being integral with the reinforcing webs adjacent the apex of the triangular-shaped web and extending in parallel spaced relation to each other beyond the triangular-shaped web and at an angle of about 90° to its long edge.

In another form of the invention the antenna mounting comprises a relatively large flat metal platform adapted to rest upon a supporting structure, an upright member attached to and extending from the upper surface of the platform for holding an antenna mast, a link pivotally connected to each of two opposite edges of the platform and being of adjustable length for leveling the platform, these links being of such a length that they are adapted to extend out to the sloping sides of a roof or other structure, and an anchor member connected to the extending ends of the links having a surface adapted to lie flat on a sloping roof surface and to be fastened thereto.

According to another feature of the invention, the improved antenna mounting device of the present invention includes adjustable link members which are adapted to facilitate installation of the device and increase the accuracy of leveling the platform. The adjustable link member furthermore provides means by which the final leveling operation may be quickly and easily accomplished after the device has been secured to the roof or other mounting structure.

Other features and advantages of the antenna mast mounting device of the present invention are

included in the following description in which the structure and arrangement of preferred forms of the device are described more in detail in connection with the accompanying drawings forming a part of this application.

In the drawings:

Fig. 1 is a perspective view showing a preferred form of an antenna mast mounting device constructed in accordance with the features of the present invention and illustrated in connection with its installation on the ridge of a roof.

Fig. 2 is an enlarged plan view of the hinge or pivot anchor attachment member shown in Fig. 1.

Fig. 3 is a side view of the hinge anchor attachment member shown in Fig. 2.

Fig. 4 is a broken perspective view similar to that of Fig. 1 showing a modified form of link and arrangement.

Fig. 5 is a broken perspective view similar to that of Fig. 4, showing a further modified form of link and assembly.

Referring to Fig. 1 of the drawings, the improved antenna mounting device of the present invention is illustrated in connection with its use on the ridge of a roof 10 for supporting and holding an antenna mast. The device includes a square base or platform 12 which is attached to the ridge of the roof by means of screws 14 which extend along a diagonal of the platform 12. In the position shown, the platform 12 is mounted so that one diagonal is in line with the ridge of the roof, while two opposite corners extend over the respective sloping sides of the roof. The screws 14 serve to initially position the platform 12 on the roof so that the weight of the mast and antenna will be carried directly by the roof.

The platform 12 may, as an example, be from five to ten inches square, and made of metal approximately one-quarter inch thick. The entire mounting device is preferably made of relatively heavy weather-resistant metal plate or cast metal, such as Duralumin, aluminum bronze, steel, iron or other suitable metal. Certain of these metals which may corrode, may be plated or painted if desired.

The corners of the platform 12 which project over the sloping surfaces of the roof, are each provided with a sheet metal anchor member 16 which may be riveted by rivets 17, or welded to the corners of the platform in the position shown. A relatively long link or bar 18 having a hole near each end is pivoted at one end to each of the anchor members 16 by means of a bolt 20, while the opposite end of each bar is similarly pivoted by a bolt 22 to an anchor plate or member 24 made exactly like the members 16. The bar 18 on each side of the ridge of the roof extends downwardly to the sloping surface of the roof, and the anchor plates or members 24 are attached to the sloping surface of the roof under a slight tension by means of screws 26.

The antenna mounting device of the present invention is erected on the ridge of the roof by initially securing screws 14, while the bars 18 and anchor members 24 extend down to the sloping surface of the roof on their respective sides. The platform 12 is then leveled crosswise of the ridge, and the anchor plates 24 are then secured to the sloping sides of the roof, with their flat sides down, by means of the screws 26. The mounting device is adapted to fit any roof slope because of the free pivots on the bolts 20 and 22 which permit the links or bars 18 to extend down to the sloping roof surface, and the members 24 to

lie flat on such surface and provide a strong anchor for maintaining the platform in horizontal position.

An important feature of the present invention is the provision of the members 16 and 24 which are of the same construction and which are therefore interchangeable in the manufacture of the device. The detailed structure of these anchor members is shown in Figs. 2 and 3, in which each member is shown as being made from a single piece of sheet metal which is relatively thin compared to the thickness of the platform 12 and the bars 18. As illustrated, each anchor comprises a triangular-shaped web 28 both surfaces of which are flat, the inside surface being adapted to fit over the corners of the platform 12 while the outside surface is adapted to fit on the flat surface of a mounting structure such as the sloping surface of the roof 10. The two equal edges of the web member 28 are each connected integrally with a flange-like reinforcing web 30 which is at right angle to the web 28, and which terminates in an ear or lug 32 provided with a hole 34 for receiving bolts 20 and 22.

As shown in Fig. 2, the ears 32 are spaced from each other a distance equal to the thickness of the bars 18, and extend at right angles to the opposite edge of the triangular-shaped web 28. The webs 30 of each anchor member extend at right angles to each other so that they exactly fit along the edges forming a corner of the square platform 12. Each of the webs 30 tapers from the ear 32 to the right hand edge of the web 28. Holes 36 are provided in the web section 28 for receiving rivets 17 or screws 26. If the members 16 are welded to the platform 12, the holes 36 may be used as anchoring points for the welds. The anchor members 16 and 24 may be cut and pressed from flat sheet, a hole preferably being punched at the juncture of the web 28 and the ears 32 to facilitate later bending of the ear and web sections 32 and 30 into position. The curved edges of such a hole are shown at 31.

The antenna mounting device of the present invention is particularly suited for the mounting of antenna masts such as are suitably employed for supporting television and frequency modulation antennas. The platform 12 therefore is provided with a mast holding member which, in the form illustrated, comprises a vertical section of pipe 38 which is welded or otherwise attached to the center of the platform 12 and which may extend substantially above the platform to receive an antenna mast 40. The mast 40 is held in any desired orientation in the pipe 38 by means of a set screw 42.

A relatively large platform 12 is preferably provided so that the sections extending along the ridge of the roof on each side of the mast holder 38 aid in preventing the tipping of the mast in the direction of the ridge of the roof. The platform 12 is relatively large for the further reason that the extending opposite diagonal corners should extend substantially over the sloping sides of the roof to provide a steady anchoring piece for the attachment of the anchors 16 and the links 18. The links 18 may be relatively long so that they extend a considerable distance down the slope of the roof. The angle between the platform and the links 18 is preferably greater than 90°, but this angle of course will vary somewhat, depending upon the slope of the roof. If desired, the members 24 may be attached to wooden cross pieces, which in turn are attached to two adjacent rafters of the roof.

The slightly modified form of antenna mounting device shown in Fig. 4, includes a platform 12 of the same construction and arrangement as that shown in Fig. 1. In this instance, the projecting diagonally opposite corners of the platform are anchored to the sloping surfaces of a roof 43 by means of an adjustable link or rod 44, one end of which is provided with a hook 46 which is hooked through the holes 34 in the anchor member 16, and with a threaded end carrying a wing nut 48. The end of the link or rod 44 carrying the wing nut, extends through a hole in a right-angle bracket member 50 which is attached to the sloping surface of the roof 43 by means of screws 52. The device shown in Fig. 4 is installed in a manner similar to that shown in Fig. 1, except that the bracket 50 is attached to each side of the roof at approximately the correct position, and thereafter the wing nut 48 on opposite sides of the roof are drawn up to level the platform 12 and hold it under a slight tension on the ridge of the roof.

A further modified arrangement of the mounting device of the present invention is shown in Fig. 5 in which a platform 54 similar to the platform 12 is mounted on the ridge of a roof 56 in a manner similar to that shown in Fig. 1. The platform 54 is a square or rectangular shaped platform in which two diagonally opposite corners project over the sloping surfaces of the roof, while the other corners are mounted on the ridge of the roof. Screws 58 serve to position the platform on the ridge.

The projecting diagonal corners of the platform 54 are each provided with a hole through which a link or rod 60 extends, the end of the rod being threaded and provided with a wing nut 62 which may have a spherical base adapted to fit into a countersunk section of the hole in the corner of the platform 54. Each of the projecting corners of the platform 54 are provided with a hole of the type referred to, which, however, is substantially larger than the rod 60, so as to permit a substantial pivoting action, so that the rod may take a substantial swing. The opposite end of the rod 60 includes a hook 64 so that the rod is of substantially the same construction as the rod 44. In Fig. 5, however, the hook 64 extends through the holes in the ears of an anchor member 66 which has the construction shown in Figs. 1 to 3. The links or rods 44, 60 or 18 may be made of adjustable length by including a turn-buckle.

The antenna mounting device shown in Fig. 5 is erected in a manner similar to that described in Fig. 4, by first attaching the screws 58, after which the nuts 62 are extended, the anchor members 66 set in place by means of screws 68, the platform then being finally leveled and tensioned down by drawing up the wing nuts 62.

The antenna mounting device provided by the present invention may be erected on various types of buildings and supporting structures in other ways than those illustrated by the drawings, which illustrate the versatility of the bracket and the fact that it can be installed with considerable ease on almost any roof or structure where the mounting of an antenna may be desirable. Furthermore, a permanent and rigid construction is provided which is easy to install and keep in proper condition, and which is adapted to support and orient a complex antenna of the type referred to above. If the antenna mast is not round it may be readily trimmed to fit the pipe 38 or be bored to fit over the pipe. A dif-

ferent form of holder from that of the pipe may be attached to the platform if desired. A pipe mast may fit over or inside the pipe section 38.

From a manufacturing standpoint, the antenna mounting device of the present invention presents no problem, but is simplified because of the interchangeability of parts and the use of a common anchor member of novel design, as described above. The bars 18 may be made of standard stock and the same is true of the rods 44 and 60. Instead of using the flat bars 18, links may be provided similar to the rods 44 and 60 which have hooks or eyes at both ends for pivoting to the anchor members 16 and 24. Such a rod having hooks may not only hook into an anchor member of the type of 16, 24, 66, but also be hooked into the anchor hole in the corner of the platform 54 instead of using the wing nut construction. Similarly, a rod having a hook on each end (at 90° to each other) may be used in the arrangement shown in Fig. 4, by hooking one end in the hole in the bracket 50, or by using the anchor member 24 in place of the anchor bracket 50. Anchor members 16, 24 and 66 may be used in connection with a rectangular shaped platform member mounted in the manner shown in applicant's pending application, Serial No. 586-547, filed April 4, 1945. The anchor members 16 may be secured to the under side of the platform, but the hood-like arrangement over the corners provides a strong and well-braced anchorage.

Various modifications and changes indicated above are contemplated as coming within the spirit and scope of the invention, as defined by the appended claims.

What is claimed as new is:

1. An antenna mounting device adapted to support an antenna on the ridge of a building roof, comprising a rigid substantially square-shaped platform member adapted to rest horizontally on said ridge with a diagonal thereof in line with the ridge, an upright mast holding member attached to and extending from the upper surface of said platform member adapted to hold an antenna mast, an anchor member attached to each of the two corners of said platform at the sides of said ridge, said anchor member including a pair of projecting lugs, a metal link pivoted to the lugs of each anchor member and extending down to the sloping sides of the roof, and a second anchor member connected to the lower end of each link for attaching the device to the roof, said second anchor member having a flat side facing the roof and adapted to be attached in a flat position onto the sloping roof surfaces.

2. An antenna mounting device adapted to support an antenna on the ridge of a building roof, comprising a rigid substantially square-shaped platform member adapted to rest horizontally on said ridge with a diagonal thereof in line with the ridge, an upright mast holding member attached to and extending from the upper surface of said platform member adapted to hold an antenna mast, an anchor member attached to each of the two corners of said platform at the sides of said ridge, said anchor member including a triangular-shaped web attached to the platform and a pair of projecting lugs, a metal link pivoted between the lugs of each anchor member and extending down to the sloping sides of the roof, and a second anchor member pivoted to the lower end of each link for attaching the device to the roof, said second anchor member having a structure similar to said first-mentioned

anchor member and adapted to be attached in a flat position onto the sloping roof surfaces.

3. An antenna mounting device adapted to support an antenna on the ridge of a building roof, comprising a rigid substantially square-shaped platform member adapted to rest horizontally on said ridge with a diagonal thereof in line with the ridge, an upright mast holding member attached to and extending from the upper surface of said platform member adapted to hold an antenna mast, an anchor member attached to each of the two corners of said platform at the sides of said ridge, said anchor member including a flat triangular-shaped web section fitting the corner of said platform and side web sections terminating in a pair of projecting lugs, a metal link pivoted to the lugs of each anchor member and extending down to the sloping sides of the roof, and means for anchoring the extending ends of said links to the sloping roof surfaces.

4. An antenna mounting device for mounting an antenna on the roofs of buildings and other structures, comprising a horizontal relatively heavy metal platform, an upright member attached to and extending from the upper surface of the platform for holding an antenna mast, an anchor member of relatively thin sheet metal attached to two opposite edges of the platform, each anchor member including a pair of lugs projecting away from the platform and providing a hinge attachment means, a brace arm hinged to each of said pairs of lugs on the opposite edges of the platform, said arms being adapted to extend out to the sloping sides of the roof or other structure, and an anchor member hinged to each of the projecting ends of said arms and having a surface to lie flat on a roof surface regardless of its slope and to be fastened thereto.

5. An antenna mounting device for mounting an antenna on the roofs of buildings and other structures, comprising a horizontal rectangular-shaped relatively heavy metal platform, an upright member attached to and extending from the upper surface of the platform for holding an antenna mast, an anchor member of relatively thin sheet metal attached to each of two diagonally opposite corners of the platform, each anchor member including a hood-like body extending over said corners and a pair of lugs projecting away from the body of the anchor member and providing a hinged attachment means, a brace arm hinged to each of said pairs of lugs on the diagonally opposite corners of the platform, said arms being adapted to extend out to the sloping sides of the roof or other structure, and an anchor member flexibly connected to each of the projecting ends of said arms and having a surface to lie flat on a roof surface regardless of its slope and to be fastened thereto.

6. In an antenna mounting device for mounting an antenna on the roofs of buildings and other structures, including a horizontal metal platform plate, an upright member attached to and extending from the upper surface of the platform for holding an antenna mast, a brace arm pivoted to each of two opposite edges of the platform, said arms being adapted to extend out to the sloping sides of the roof or other structure, and an anchor member connected to each of the projecting ends of said arms and having a surface adapted to lie flat on a roof surface regardless of its slope and to be fastened thereto, an improved anchoring means for pivoting said brace arms to the platform comprising a sheet

metal web attached to the platform, integral webs extending from said web and providing a pair of ears to which a brace arm is pivoted.

7. In an antenna mounting device for mounting an antenna on the surface of buildings and other structures, including a substantially square-shaped flat metal platform, an upright member attached to and extending from the upper surface of the platform for holding an antenna mast, a link pivotally connected to each of two diagonally opposite corners of the platform, said links being adapted to extend out to the sloping sides of the roof or other structure, an anchor member connected to each of the projecting ends of said links and having a surface adapted to lie flat on the roof surface regardless of its slope and to be fastened thereto, an improved pivot structure between each link and the platform, comprising a sheet metal web attached to the platform, integral webs extending from said web and providing a pair of ears, and a hook on the end of the link pivotally connected to said ears.

8. An antenna mounting device as defined by claim 7 in which each pair of ears is provided with matching holes, and in which the hook on the link pivotally connected thereto extends through the holes in said ears.

9. In an antenna mounting device for mounting an antenna on the surface of buildings and other structures, including a flat metal platform having a pair of oppositely projecting corners, an upright member attached to and extending from the upper surface of the platform for holding an antenna mast, a link pivotally connected to each of said opposite corners of the platform, said links being of adjustable length and adapted to extend out to the sloping sides of the roof or other structure, an anchor member connected to each of the projecting ends of said links and having a surface adapted to lie flat on the roof surface regardless of its slope and to be fastened thereto, an improved pivot structure between each link and the platform, comprising a sheet metal web attached to the platform, integral webs extending from said web and providing a pair of ears, and a hook on the end of the link pivotally connected to said pair of ears.

10. An antenna mounting device for mounting an antenna on the roofs of buildings and other structures, comprising a substantially square flat relatively heavy metal platform, an upright member attached to and extending from the upper surface of the platform for holding an antenna mast, an anchor member attached to each of two diagonally opposite corners of said platform, a link pivotally connected by one end to each of said anchor members, said links being adapted to extend out to the sloping sides of the roof or other structure, an anchor member connected to the projecting end of each of said links and adapted to be attached to a roof surface regardless of its slope, at least one of said anchor members connected to each link comprising a flat sheet metal web, a pair of integral webs extending from said web and providing a pair of ears to which an end of a link is attached by a pivot connection.

11. An antenna mounting device as defined by claim 10 in which a hook is provided on at least one end of each link and pivotally connected to the pair of ears of an anchor member.

12. An antenna mounting device for mounting an antenna on the roofs of buildings and other structures, including a relatively large flat metal

platform adapted to rest on a supporting structure, an upright member attached to and extending from the upper surface of the platform for holding an antenna mast, a link pivotally connected to each of two opposite edges of the platform, said links being of adjustable length for leveling said platform and adapted to extend out to the sloping sides of the roof or other structure, and an anchor member connected to the extending ends of said links and having a surface adapted to lie flat on a roof surface regardless of its slope and to be fastened thereto.

13. An antenna mounting device for mounting an antenna on the roofs of buildings and other structures, including a relatively large flat metal platform adapted to rest upon a supporting structure, an upright member attached to and extending from the upper surface of the platform for holding an antenna mast, a link having a hook at one end and pivotally connected to each of two opposite edges of the platform by an end pivot, said links being of adjustable length for leveling said platform and adapted to extend out to the sloping sides of the roof or other structure, and an anchor member connected to the extending end of each of said links and having a surface adapted to lie flat on a roof surface regardless of its slope and to be fastened thereto.

14. An antenna mounting device for mounting an antenna on the roofs of buildings and other structures, including a substantially square-shaped flat metal platform, an upright member attached to and extending from the upper surface of the platform for holding an antenna mast, an anchor member attached to each of two diagonally opposite corners of the platform, a link pivoted to each of said anchor members by an end joint, said links being adapted to extend out to the sloping sides of a roof or other structure, and an anchor member connected to each of the extending ends of said links and having a surface adapted to lie flat on a roof surface regardless

of its slope and to be fastened thereto, at least one of the anchor members connected to each link comprising a flat right-triangular-shaped sheet metal web, a reinforcing web integral with said web and extending normal thereto from each of the equal edges of said web, and an ear integral with each of said reinforcing webs adjacent the apex of said flat web, said ears extending in parallel spaced relation to each other beyond said flat web and at an angle of about 90° to its long edge.

15. In an antenna mounting device for mounting an antenna on a structural member such as the roofs of buildings, or other structure, a substantially square flat relatively heavy metal platform member, an upright means attached to and extending from the upper surface of the platform member for holding an antenna mast, a link pivotally connected to each of two diagonally opposite corners of said platform member, said links being adapted to extend out to the sloping sides of a roof or other equivalent structural member, and an anchor means pivotally connected to at least one end of each of said links and adapted to be attached to one of said members, said anchor means comprising a flat sheet metal web having a pair of integral webs extending therefrom and providing a pair of ears to which an end of a link is attached by a pivot connection.
